No. 664,669.

Patented Dec. 25, 1900.

C. NORDHAUGEN.

OIL CAN.

(Application filed Apr. 9, 1900.)

(No Model.)

UNITED STATES PATENT OFFICE.

CARL NORDHAUGEN, OF ANETA, NORTH DAKOTA, ASSIGNOR OF ONE-HALF
TO JOHN G. GUNDERSON, OF SAME PLACE.

OIL-CAN.

SPECIFICATION forming part of Letters Patent No. 664,669, dated December 25, 1900.

Application filed April 9, 1900. Serial No. 12,161. (No model.)

To all whom it may concern.

Be it known that I, CARL NORDHAUGEN, a citizen of the United States, residing at Aneta, in the county of Nelson, State of North Dakota, have invented certain new and useful Improvements in Oil-Cans, of which the following is a description, reference being had to the accompanying drawings and to the letters of reference marked thereon.

10 My invention relates to improvements in oil-cans, and more particularly to that class of such devices in which the oil is forced therefrom.

15 My objects are to provide a means for regulating the amount of oil fed at each operation of the parts, to permit the outlet port or ports to be closed and the parts locked in this position, and to provide a structure of can which can be readily filled and in which the plunger and its attached parts can be quickly and conveniently withdrawn for cleaning, repair, &c.

20 To these ends and also to improve generally upon devices of the nature indicated my invention consists in the various matters hereinafter described and claimed.

25 In the accompanying drawings, Figure 1 is a central sectional elevation of the present can, the spring and plunger-rod, however, being shown in side elevation; and Fig. 2 is a bottom plan view, this view showing the plunger-cap in the position it occupies when the parts are locked in position to close the outlet-ports.

30 Referring now more particularly to the drawings, A represents the can-body, having the spout a and provided with a depressed or cone-shaped bottom a'. A central tube A' extends longitudinally through the can-body,

35 the upper end of the same forming the spout a, while its lower end extends through the can-bottom. Near the upper end of the can-body this tube is provided in its walls with ports a², through which the contents of the

40 can proper can pass into the tube, to be expelled therefrom by means of a plunger operating in the tube, said tube thus forming a chamber to receive oil from the can proper, said chamber also communicating with the

45 spout. The plunger comprises a head b, a rod b', attached thereto, and a cap b², to which

the said rod is also connected. Said cap projects beyond the tube end and is normally held in this extended position by means of a spring C, which bears against the cap and a 55 suitable portion of the tube. When the cap is in this normal position, the plunger-head rests below the ports a²—i. e., at the side of the ports opposite the spout—ready to expel from the can-spout the oil which has been 60 drawn into the tube from the can-body when the plunger moved into the position indicated. Manifestly the amount of oil drawn into the tube and expelled therefrom by the action of the plunger is determined by the distance be- 65 low the ports a² to which the plunger-head moves when returning to normal position, and in order to regulate this I provide means for adjusting the distance between the plunger- 70 head and the cap, the normal position of the cap being rendered constant by the spring C. This adjustment is accomplished by reason of the threaded rod end, which enters a correspondingly threaded seat in the cap. The plunger-head of course fits snugly within the 75 tube, so that by rotating the cap this is screwed one way or the other along the plunger-rod, thus, in effect, varying the length of the plunger, and consequently adjusting the normal position of the plunger-head with relation 80 to the ports, the cap being, as previously explained, normally held in a constant position and its amount of inward movement being limited by its laterally-extending flange b³ con- 85 tacting with the can-bottom. By reason of the construction just explained the operator can set his plunger to deliver a large or small quantity of oil at each operation. The flange b³ is eccentric with relation to the cap, whereby it presents, in effect, a projection upon one 90 side of said cap, and a lug or catch a³ is suitably provided upon the can-bottom. The plunger parts are so proportioned that when the cap is forced inwardly to bring the flange between the said lug and the end of the tube 95 A' the plunger-head lies across and covers the ports a². When, therefore, the parts are brought into this position and the cap turned to bring the wider portion of the flange above the said lug—i. e., between the lug and the 100 tube end—said lug lies in the path of movement of the flange, and thus locks the head

in position, closing the ports a^2 and preventing accidental discharge from the can. The can can then be safely carried in a tool-bag. When it is desired to operate the can, the cap 5 is turned to carry the wider flange portion out of contact with the lug, and the plunger can then be readily reciprocated.

It will be noticed that the bottom portion of the tube A' is of greater diameter than is 10 its body portion, whereby there is produced the inwardly-extending shoulder a^4 . This shoulder forms a seat for the inner end of the spring C , (which spring is preferably spiral and encircles the plunger-rod,) while the 15 outer spring end is attached to the cap, as by means of an ear a^5 , upon said cap bent over upon the spring. Thus the plunger and spring are only frictionally held within the tube and can be readily withdrawn for cleaning, repair, &c. Furthermore, when the plunger is thus withdrawn and the can inverted, 20 with the air-vent a^6 open, said can can be filled by simply pouring the oil upon the bottom, the inclined walls of which cause it to act 25 as a funnel. By closing the air-vent and reinserting the plunger the can is again ready for operation.

The present can is simple in its construction and its parts can be readily assembled. 30 The discharge of oil can be regulated, the parts locked in position to close the outlet-ports, the can can be easily and quickly filled, and the plunger and its spring readily withdrawn for cleaning or repair. The device is 35 a cheap and efficient oiler.

Having thus described my invention, what I claim as new, and desire to secure by Letters Patent, is—

1. In an oil-can or the like, a plunger adapted to expel the oil in its movement, said plunger comprising a plunger-head, an exterior cap under the control of the operator, and connection between said cap and head, said connection including means whereby the distance 45 between the said cap and head can be adjusted; substantially as described.

2. In an oil-can or the like, a plunger adapted to expel the oil in its movement, said plunger comprising a plunger-head, an exterior cap under the control of the operator, telescoping connection between said cap and head whereby the distance between said parts can 50 be adjusted, and means for holding said parts in adjusted position; substantially as described.

3. In an oil-can or the like, a plunger adapted to expel the oil in its movement, said plunger comprising a plunger-head, an exterior cap under the control of the operator, and a 60 plunger-rod connecting said head and cap and having threaded connection with one of them, the threads extending a greater distance than that necessary for engagement only, whereby the distance between said cap and head can 65 be adjusted; substantially as described.

4. In an oil-can or the like, a plunger adapted to expel the oil in its movement, said plun-

ger comprising a plunger-head, an exterior rotatable cap under the control of the operator, and a plunger-rod connecting said head and cap and having threaded connection with one of them, the threads extending a greater distance than that necessary for engagement only, whereby the distance between said cap and head can be adjusted; substantially as described.

5. In an oil-can or the like, a chamber communicating with the spout and having a port connecting it with the can proper, a plunger movable across said port to expel oil from said chamber, a flange projecting from one side of said plunger, and a lug upon the can, whereby said plunger can be brought across the said port to close the same and turned to cause its flange to engage the lug to lock the 85 parts in the position indicated; substantially as described.

6. In an oil-can or the like, a tube having an enlarged portion opening through a wall of the can, a shoulder being produced between 90 the body portion and enlarged portion of said tube, said tube communicating with the spout and having a port connecting it with the can proper, a plunger operating in said tube and having a cap freely movable into and out of 95 said enlarged portion, and a spring bearing against said shoulder and said cap, whereby said plunger and spring can be withdrawn from the tube; substantially as described.

7. In an oil-can or the like, a tube having 100 an enlarged portion opening through a wall of the can, a shoulder being produced between the body portion and enlarged portion of said tube, said tube communicating with the spout and having a port connecting it with the can 105 proper, a plunger operating in said tube and having a cap freely movable into and out of said enlarged portion, and a spring connected to said cap and bearing against said shoulder, whereby said plunger and spring can be 110 withdrawn from the tube; substantially as described.

8. In an oil-can or the like, a tube having an enlarged portion opening through a wall of the can, a shoulder being produced between 115 the body portion and enlarged portion of said tube, said tube communicating with the spout and having a port connecting it with the can proper, a plunger operating in said tube and having a cap freely movable into and out of 120 said enlarged portion, a spring bearing against said shoulder and said cap, and an ear upon said cap bent over upon the spring and securing the same to the cap, whereby said plunger and spring can be withdrawn from the 125 tube; substantially as described.

9. In an oil-can or the like, a chamber communicating with the spout and also having a port connecting it with the can proper, a plunger movable in said chamber across said port 130 to expel the oil therefrom through said spout, the plunger-head being movable to the side of the port opposite the spout, a rotatable cap under the control of the operator, means for

- limiting the throw of said cap, connection between said cap and plunger-head whereby said parts are caused to move together, means for varying the distance between said cap and plunger-head to regulate the amount of oil expelled at each operation of the plunger, a flange projecting from one side of said plunger and serving to limit the throw of the same by engaging the can-body, and a lug upon the can, whereby said plunger can be brought across the said port to close the same and turned to cause its flange to engage the lug to lock the parts in the position indicated; substantially as described.
10. In an oil-can or the like, a chamber communicating with the spout and also having a port connecting it with the can proper, a plunger movable in said chamber across said port to expel the oil therefrom through said spout, the plunger-head being movable to the side
- 15 of the port opposite the spout, a rotatable cap under the control of the operator, a plunger-rod connecting said head and cap and having threaded connection with one of them, whereby the distance between the cap and plunger-²⁵ head can be adjusted, a flange projecting from one side of said plunger and serving to limit the throw of the same by engaging the can-body, and a lug upon the can, whereby said plunger can be brought across the said port to close the same and turned to cause its flange to engage the lug to lock the parts in the position indicated; substantially as described.
- 20 In testimony whereof I affix my signature in presence of two witnesses.
